UNITED STATES PATENT OFFICE.

EDGAR V. PHILLIPS, OF JAMESTOWN, NEW YORK.

COMBINATION FRUIT-JAR OPENER AND SEALER.

Application filed November 23, 1921. Serial No. 517,392.

To all whom it may concern:

Be it known that I, EDGAR V. PHILLIPS, a citizen of the United States, residing at the city of Jamestown, in the county of Chautauqua and State of New York, have invented certain new and useful Improvements in Combination Fruit-Jar Openers and Sealers, of which the following, taken in connection with the accompanying drawings, is a specification.

The invention relates to implements for attaching upon and removing caps from fruit jars, powdered milk jars and similar receptacles; and the object of the improvement is to provide a simple and strong clamping construction adapted to the different styles and sizes of jars now being used, so that the jars may be opened or sealed with a minimum amount of strength, the angular knife for breaking the rubber seal being placed at the point of highest leverage, and both jaws of the clamping members are constructed to engage the different types of jars; and the invention consists in the novel features and combinations hereinafter set forth and claimed.

In the drawings, Figure 1 is a plan view of the fruit jar opener showing the preferred form and arrangement of the parts. Fig. 2 is a side elevation of the same. Fig. 3 is a sectional view at line 3—3 in Fig. 1 showing the preferred arrangement adjacent the hinging joint between the two parts of the clamping tongs. Fig. 4 is a sectional view at line 4—4 in Fig. 1 showing the action of the angular knife in breaking the rubber seal. Fig. 5 is a sectional view at line 4—4 in Fig. 1 with the clamping members reversed as used for opening the small size threaded or so-called "Mason" type of fruit jars. Fig. 6 is a plan view of the hinged joint between the clamping members showing a modification of the single hinge joint whereby the distance between the clamping members may be enlarged. Fig. 7 is a sectional view at line 4—4 showing the clamping members in position as used for opening the large size threaded or so-called "Mason" jars. Fig. 8 is a view of the slip joint similar to the one shown in Fig. 6 with the exception that the pintle bolt is shown in section to show its flat sides; and Fig. 9 is an elevation of said pintle bolt removed from the jaws of the clamping tongs.

Like characters of reference refer to corresponding parts in the several views.

The numeral 10 designates one of the clamping members, and the numeral 11 the other, which members are hinged to one another usually by the hinge pintle 12 in single holes in the ends of the clamping members opposite the handles.

Among the vacuum or semi-vacuum sealing cap jars, there are a number of different types, the threaded or so-called "Mason" cap in two different sizes, and the so-called Lightning or Atlas type both with rubber seals. The jaws 10 and 11 of the clamping members are arranged to fit and attach or remove, that is, seal or open, the cap or top of the fruit jars of the different types.

In order to grasp the smaller size threaded type of jar which is shown in Fig. 5 and designated by the numeral 13, the spaced toothed inward projections 14 are provided preferably four in number. These might be continuous on each jaw, but this is unnecessary, the toothed portions being more adaptable to the contour than the continuous toothed projection and more readily fitting to different jar tops since said jar tops are not always alike though supposedly the same.

For the larger type of the screw cap or "Mason" fruit jars, as shown at 15 in Fig. 7, the inner side of the rim portion 16 of the two jaws is toothed to clasp onto the screw cap 17 when turning the same onto or off from the jar 15.

In order to open the rubber-sealed or so-called Lightning or Atlas type of jars, a downwardly and inwardly projecting knife 18 is provided preferably on the right jaw a short distance from the hinging pintle 12 in order to obtain a large leverage on said knife 18 in forcing it into the joint between the rubber 19 and jar 20 or jar cap 21.

In order to hold the knife 18 to its work and in position to enter the joint between the cap 21 and rubber 19, a downward projection 22 is provided on the jaw 11 opposite the knife 18 to hold against the same on the opposite side of the jar and cap. Inward projections 23 and 24 are also provided on the jaw 11 opposite the knife 18 which rest upon the top of the cap 21. A spring 25 is attached to the jaw 10 near the knife 18 so as to spring up over the top of a round cap 21 and ensure holding the same, and also spacing the distance correctly from the knife 18 so that said knife will invariably seek the joint between the cap 21 and

the jar 20. The projections 23 and 24 and spring 25 hold all known forms of caps like 21 firmly while the angular knife 18 is being inserted in the packed joint to break 5 the vacuum suction on the cap 21.

In order to enlarge the space between the jaws 10 and 11, a slip joint 26 may be provided in place of the single pintle hinge 12 in which the dumb bell shaped slot 27 is 10 provided in one jaw 28, while the bolt 29 extends through a single round opening in the jaw 30. The bolt 29 has the flattened sides 31 so that the jaws 28 and 30 may be opened sufficiently to permit the slipping 15 of the bolt 29 from one circular end to the other of the slot 27, thereby diminishing or enlarging the slot as desired, yet giving a positive gripping hold for the jaws on the hinging bolt or pintle 29 in the circular ends 20 of said slot 27. This arrangement provides for the enlargement of the space between the circular portions of the clamping members so as to adapt said members for use upon large jars, as, for example, the hospital size of powdered milk jars, the caps of 25 which often fit so tightly upon the threaded neck of the jar as to be difficult of removal.

The circular jaws of the clamping members 10 and 11 are preferably made of sufficient width to provide the inturned knife 18 on one side of the jaw 10 and the opposite holding projection 22 on the jaw 11. The reverse side of said circular jaw has the spaced toothed inward projections 14 therein. Said reverse sides of said jaws extend a distance about equaling the width of said toothed inward projections 14 and are continuously toothed or serrated as shown at 16, the toothed serrations forming strong 20 holding means for the larger sizes of screw caps 17, which serrated portion, taken with the slip joint 26, enables the user of the tool to open large caps.

What is claimed as new is:

1. A tool of the class described, comprising two semi-circular shaped jaws hinged to each other, handles on said jaws, and a plurality of different sized fixed toothed curves on different levels on said jaws to 25 clampingly fit jar caps of relatively large and small sizes.

2. A tool of the class described comprising two semi-circular shaped jaws hinged to each other having handles thereon, spaced toothed curved projections on the inner sides of each of said jaws to grip the cap of the jar or bottle of relatively small diameter, inward projections attached to and alongside said spaced inward projections to rest upon 10 the top of the cap, said jaws having toothed

serrations around the inner side of the same and alongside said inward toothed projections to engage a larger size cap than said inward toothed projections.

3. In a tool of the class described, the combination of semi-circular shaped jaws hinged to each other, handles on said jaws spaced toothed projections on the inner sides of each of said jaws to grip the cap of the jar or bottle, flat inward projections attached to said spaced inward projections to rest upon the top of said cap, a projection on one of said jaws in the circular plane thereof and on the reverse side from said toothed projections, and an angular inturned 75 knife on the opposite jaw from said projections spaced to enter the sealing joint of a jar to break the vacuum suction and open said jar.

4. In a tool of the class described, the combination of semi-circular shaped jaws hinged to each other at one end and handles on the other ends, spaced toothed projections on the inner sides of each of said jaws to grip the cap of one type of jar or 35 bottle, inward projections attached to said jaw alongside said spaced inward projections to rest upon the top of said cap, a projection on one of said jaws in the circular plane thereof and on the reverse side from 40 said toothed projection, an inturned knife on the opposite jaw from said projection spaced to enter the sealing joint of a jar to break the vacuum suction to open said jar, and a spring attached to the jaw alongside 45 said knife and spaced therefrom to resiliently hold the jar cap in opening the jar.

5. In a tool of the class described, the combination of semi-circular shaped jaws, a slip joint hinging connection between said 100 jaws at one end to form a pair of clamping members capable of enlargement, handles on the other ends of said semi-circular jaws, spaced toothed inward projections on the inner sides of said jaws, an inwardly projecting 105 leaf spring on one of said toothed projections, an inwardly projecting knife a spaced distance from said spring corresponding substantially to the thickness of a jar cap, and toothed serrations around the 110 circular portions of said jaws on the reverse side from said knife to clampingly engage screw caps and similar jar closures.

In testimony whereof I have affixed my signature in the presence of two witnesses. 115

EDGAR V. PHILLIPS.
